PROCESS FOR THE MAKING OF ARTIFICIAL FLOWERS

Carmen von Brun, born Buelle, Berlin, Germany

Application August 18, 1937, Serial No. 159,718
In Germany March 27, 1936

2 Claims. (Cl. 41—13)

The object of the invention is to introduce a new process for the making of artificial flowers from stretched out crepe-paper with the aid of a former. The formers used in this invention are adapted to the natural shape of the petals and blossoms and have handles to them. Its application is shown in the description of how the process is carried out. The execution of this invention is not only simple and the making material of little cost; paper and adhesive being the chief component parts, but the manner of making the flower is simplified by its attachment to the ovary, in a way which constitutes an important technical improvement.

15 In the accompanying drawing:

Figure 1 is a perspective view illustrating a wad of material being placed upon a strip of paper preparatory to folding the paper over the wad and then twisting the paper to form the 20 ovary pad and stem of the flower;

Fig. 2 illustrates the paper being folded over the wad;

Fig. 3 illustrates the paper as having been folded and pressed about the wad to constitute a ball 25 forming the ovary pad;

Fig. 4 illustrates the paper as having been tightly twisted below the pad to constitute the stem of the flower;

Fig. 5 illustrates the ovary pad being pierced 30 with a pointed tool to form a hole therein;

Fig. 6 shows the petal assembly as having been placed over the ball or ovary pad;

Fig. 7 indicates the petal assembly and a small 35 piece of adhesive bearing material being pressed into the preformed hole in the ovary pad by a pointed instrument;

Fig. 8 shows a former, hereinafter described, about to be placed in position to have the petals folded up therearound and shaped thereby;

Fig. 9 illustrates the petals folded up around the former;

Fig. 10 is a plan view of one or more petal forming paper blanks, hereinafter described;

Fig. 11 is a view of Fig. 10 showing a plurality 45 of thin paper disks or leaves of different colors, placed over the paper blank of Fig. 10;

Fig. 12 is a plan view of the assembly of Fig. 11, with a small piece of paper centrally disposed thereon which, when pressed inwardly by a tool 50 constitutes the paper tack hereinafter described, and

Fig. 13 is a view partly in section and partly in elevation of the former, hereinafter described.

Like numerals designate corresponding parts 55 throughout the several figures of the drawing.

The process is carried out as follows: A small wad 5, of cellulose or cotton wadding, is placed near one end of a strip of stretched out crepe paper 6, and the adjacent end portion of the paper is folded over the wad as indicated at 7 in Fig. 2. 5 This folded over end is then pressed and twisted about the wad to form a ball-like protuberance 8, constituting the ovary pad of the completed flower. The paper below this pad is then tightly twisted to form a paper stem 9 for the flower. 10

The formation of the ball or pad 8 may be facilitated by wetting the thumb and forefinger in twisting the folded over end of the paper snugly and tightly therearound, preparatory to continuing the twisting to form the stem 9. Thus it 15 will be seen that the stem and pad are formed in one integral piece in so far as the paper, constituting the same, is concerned.

The petal assembly is formed by cutting paper blanks 10 to suitable form, these blanks comprising the central portion, surrounded by radial projections 10^a, of suitable shape. Small paper disks or leaves 11, successively diminishing in size (see Fig. 11) are then placed upon the blank 10. 20 These disks may vary in number and are preferably of different colors. Further, I preferably use two or more layers of the petal blanks 10 and stick them lightly together with adhesive, because this gives the paper more body and consistency. The leaves or disks 11 are also touched 25 lightly with adhesive to hold them in place.

With any suitable pointed tool, indicated in a general way at 12, a hole 13 is formed in the center of the ovary pad 8. A small amount of adhesive is placed in this hole and the petal assembly is placed centrally over the top of the hole. 35 A small piece of paper, indicated at 14 in Figs. 7 and 12, is supplied with a small amount of adhesive and is placed centrally over the petal assembly. The tool point 12 (Fig. 7) is then used 40 to thrust this piece of paper or equivalent material and petal assembly into the preformed hole in the pad 8. This brings this piece of material 14 to the form of a paper tack, having a central opening therein.

This piece of material 14 forms the calyx of the flower while at the same time it unites, in the most simple and natural way, stem, pad, petals and calyx into a flower and fixes them firmly together. This constitutes an essential feature 50 of my new and simplified process, without which the production of these flowers would not be feasible. The application of the adhesive to the material 14 unites the paper tack to the petal assembly, while the insertion of the adhesive into 55

the pre-formed hole in the pad 8 unites the petal assembly to the pad.

For some kinds of flowers, the process so far described is sufficient. However, for other kinds of flowers, such for example as those of the bell or trumpet-shaped type, it becomes desirable to bring the edges of the petals into overlapping relation and to unite them with each other. When that is to be done, the former of Fig. 13 is employed. In using this former, it is placed centrally within the flower, with the recess 16 fitted over the calyx. A little adhesive is then applied to one edge of each of the petals, and the petals are pressed into engagement with the forming face, 16^a, of the former.

If, for example, the adhesive is applied to the left side of each petal leaf, the petal leaves are lapped one over the other against the former by using the left-hand thumb and forefinger, working all around the flower. When the rounding is complete, the operator keeps hold of the pressed petals with the fingers and thumb of the left hand, and with the right hand draws the former, while slightly rotating it, out of the molded flower, as illustrated in Fig. 9.

Thus it will be seen that I am able to easily and quickly form artificial flowers having petals of one color, centers of a plurality of colors where desired, and a calyx presenting a very natural appearance, all of these parts being very firmly united in a simple and speedy operation.

I claim:

1. The herein described process for the making

of artificial flowers from crepe paper, comprising the steps of folding an end of a strip of such paper about a ball of wadding and then twisting the strip of paper tightly into stem formation, so that said paper and wadding ball form a stem and ovary pad, preparing the petals by shaping a paper disk to form a plurality of radial projections extending from a common center, placing upon said common center one or more small round disks of paper, differing in color from the petals and being secured with adhesive to the petal disk, piercing a hole in the middle of the ovary pad, placing the prepared petals centrally on top of the hole, attaching the prepared petals to the ovary pad by pressing a small piece of material, carrying adhesive, together with the petals into the hole, so that such piece of material is caused to take the shape of a paper tack or nail.

2. The process as recited in claim 1, in combination with the additional step of applying adhesive to one edge only of each of the petals and thereafter pressing all of said petals about a former, toward the axis of the flower, with the edges of the petals overlapping in such manner that the adhesive upon the edge of one petal is caused to attach said petal to the adjacent petal, whereby the flower is brought to and held in bell-like or cup-shaped formation.

CARMEN VON BRUN, BORN BUELLE.
